UNITED STATES PATENT OFFICE

GEORGE E. BALL, OF CRANSTON, RHODE ISLAND, AND PERCY B. BALL, OF ATTLEBORO, MASSACHUSETTS, ASSIGNORS TO CHESBROUGH MANUFACTURING CO., CONSOLIDATED, OF NEW YORK, N. Y., A CORPORATION OF NEW YORK

DESIGN FOR A RING

Application filed October 25, 1932. Serial No. 45,580. Term of patent 3½ years.

To all whom it may concern:

Be it known that we, GEORGE E. BALL and PERCY B. BALL, citizens of the United States, residing, respectively, at Cranston, in the county of Providence and State of Rhode Island, and at Attleboro, in the county of Bristol and State of Massachusetts, have jointly invented a new, original, and ornamental Design for Rings, of which the following is a

specification, reference being had to the accompanying drawing, forming part thereof.

Figure 1 is a perspective view of a ring, showing our new design, and Figure 2 is a developed plan view of the same.

We claim:

The ornamental design for a ring, as shown.

GEORGE E. BALL.
